VENDING DEVICE

Filed June 11, 1928

INVENTOR
LAWRENCE M. REDLINGER
BY C. F. Blaue, A.T.T.

UNITED STATES PATENT OFFICE.

LAWRENCE M. REDLINGER, OF PORTLAND, OREGON.

VENDING DEVICE.

Application filed June 11, 1928. Serial No. 284,563.

My invention relates to vending devices in general, and particularly to such devices as are adapted for the vending of apples and like fruit, the object being to provide a 5 simple, attractive and cheap device for the display of the fruit from which it may be removed one piece at a time as purchased. I accomplish this object by means of the construction illustrated in the accompanying 10 drawing, which is a part of this application for Letters Patent, like characters of reference indicating like parts throughout the several views thereof, and in which:

Fig. 1 is a sectional side elevation of my 15 device.

Fig. 2 is a section upon the line 2—2 of Fig. 1.

Fig. 3 is a section upon the line 3—3 of Fig. 1.

Fig. 4 is a perspective view of my device.

The device consists of a box-like structure having sides 5, top 6, and bottom 7. Rising from the bottom and connecting the sides is a back 8 which extends only partly 25 to the top, the remaining back space being closed by a door 9 hinged to the back 8. The front of the structure consists of a vertical portion and an inclined portion. Said inclined portion is provided with a transparently closed opening, as of glass 10, through 30 which to view the displayed fruit. The lower end of the vertical front 11 and the forward end of the bottom 7 are joined by a cylindrical portion 12 having a hinged door 13.

Within said structure are provided ways 40 for the fruit, consisting of guides to lead the fruit to the dispensing device below. These guides are preferably constructed in an integral unit which is mounted within the structure in such a manner that it may be adjusted for various sizes of fruit.

Said ways are constructed of a transversely disposed top member 14 and a corresponding bottom member 15. At each end 45 of said members 14 and 15, adjacent the sides of the box-like structure, there is provided a connecting member 16, rigidly secured upon each of the members 14 and 15. Said members 16 extend downwardly in an inclined portion 16^a substantially parallel to the glass 10, a backwardly curved portion 16^b, and a backwardly extending horizontal portion 16^c, and at the point of juncture of 50 portions 16^b and 16^c the member 15 is se-

cured thereto. The rear end of the portion 16^c is downwardly bent and formed into a portion 16^d adapted to fit into orifices 17 in the structure bottom 7.

Intermediate said side members 16 are 60 provided similar members, in plurality, designated as 18, together with the members 16 these members form runways for the fruit, as shown in Fig. 1. There may be as many such runways as the size of the device 65 will accommodate, three being shown in the drawing. The members 18 terminate at the lower member 15, conveniently being simply bent around said member in the form of an eye 19.

Between each of said runways there is a 70 guide member to prevent the fruit in one runway interfering with the fruit in the adjacent runway. These guides are formed similarly to the runway members 16 and 18. 75 They are secured to the upper member 14, and therefrom extend substantially parallel to the members 16 and 18, having the same downwardly inclined portions 20 and rearwardly curved portion 21. At the lower 80 end of the portions 21 they are given a sharp forward and reverse bend, thus forming a loop portion 22. Rearwardly extending legs are provided to secure these guide members to the cross members 15 and 14, said 85 legs being designated as 23 and 24 respectively. These legs set the guide members out from the runway members sufficiently so that the guides contact with the fruit at substantially its middle zone.

Below the reverse bent portion 22 of the 90 guide members I provide means for dispensing the fruit. This may be simply a door in the structure, but preferably it consists of a cylinder 26 rotatably mounted within the 95 cylindrical portion 12 of the structure by means of a shaft 27 which is provided with an outer handle 28 whereby to rotate the cylinder. Said cylinder is provided with fruit receiving pockets, one for each runway and aligned therewith, designated by 29. The peripheral arrangement of said pockets upon said cylinder is such that while one is registered with the door 13 another is registered with one of the runways, and the rest 100 are disposed between said door and their respective runways. Therefore in any position of the cylinder 26 there will be one piece of fruit disclosed upon opening the door 13, and another piece of fruit deposited 110

within its respective pocket, the other pockets being already filled and ready to be registered with the door in their turn, or empty and ready to be filled from the runway when presented thereto.

To prevent the fruit from congesting in the space above the cylinder, by which congestion the fruit might become injured, I provide an inwardly directed and downwardly inclined deflector 30 secured to the front of the structure adjacent the point where the vertical portion 11 thereof joins the inclined portion wherein is positioned the glass 10. As the fruit moves downward within the runways it comes into contact with said deflector as shown in dotted lines in Fig. 1, and is thereby guided around the turn of the runways from the inclined portion 16^a thereof into the curved portion 16^b thereof,—otherwise the fruit would pile up and become congested in the space immediately above the cylinder 26. To still further confine the fruit within the respective runways I provide yieldable spring tongues 31 secured to the deflector 30 and depending therefrom adjacent the respective runways. These yieldable tongues will contact with the fruit if it leaves the runway and gently restore it to the runway.

To adjust the device to various sizes of fruit I mount the upper cross member 14 in brackets 33 notched to receive said member, and the lower ends of the members 16, 16^a I mount within the orifices 17 in the structure bottom 7. Thus by mounting the upper member 14 in a notch in the brackets 23 that corresponds in position relative to the front of the device with the orifice in which the ends 16^a are mounted, the whole runway unit may be mounted at various distances from the front of the device, thus accommodating various sizes of fruit.

My invention may be used in combination with various coin operating devices, said devices communicating with a coin receiv-

ing slot 40, but since such coin operating devices are well known to the vending machine art, and form no part of my present invention they are not described herein nor shown in the drawing. As described and illustrated the device is simply a mechanical clerk to deliver the goods in perfect condition.

My device may be made of any size, and constructed of any materials deemed convenient and suitable for a device of this character, and while I have illustrated and described a form of construction and arrangement of parts found desirable in materializing my invention, I wish to include in this application all mechanical equivalents and substitutes that may fairly be considered to come within the scope and purview of my invention as defined in the appended claim.

Having disclosed my invention so that others may be enabled to construct and to use the same, what I claim as new and desire to secure by Letters Patent is:

In a fruit vending device: an inclosing structure having an inclined transparently closed display opening; runways within said structure having an upper portion substantially parallel to said display opening and a lower portion disposed substantially vertically; an inwardly projecting deflector adjacent the juncture point of said portions of the runways for the purpose of guiding the fruit from one portion of the runway to the other portion thereof to prevent congestion of the fruit at the lower end of the runway; and an opening in said structure through which fruit at the lower end of the runway may be removed.

In witness whereof I claim the foregoing as my own I hereunto affix my signature at Portland, county of Multnomah, State of Oregon, this 17th day of Apr., 1928.

LAWRENCE M. REDLINGER.
